GARMENT HANGER OR THE LIKE

Audrey E. Buchanan, Pico, Calif.

Application August 20, 1951, Serial No. 16,384

Term of patent 3½ years

(Cl. D80—8)

To all whom it may concern:

Be it known that I, Audrey E. Buchanan, a citizen of the United States, and residing at Pico, county of Los Angeles, State of California, have invented a new, original, and ornamental Design for a Garment Hanger or the like, of which the following is a specification, reference being had to the accompanying drawing, forming part thereof.

In the drawing:

I claim:

The ornamental design for a garment hanger or the like, substantially as shown.

AUDREY E. BUCHANAN.
